United States Patent Office

Des. 211,921
Patented Aug. 6, 1968

211,921

COMBINED ASHTRAY AND CIGARETTE SNUFFER

John B. Bourgeois, 142 Beacon St.,
Worcester, Mass. 01610

Filed Aug. 3, 1967, Ser. No. 8,103

Term of patent 14 years

(Cl. D85—2)

FIG. 1

FIG. 2

FIG. 1 is a view in elevation of a combined ashtray and cigarette snuffer showing my new design, and

FIG. 2 is a plan view thereof looking in the direction of arrow 2 in FIG. 1.

I claim:

The ornamental design for a combined ashtray and cigarette snuffer, as shown.
